CONNECTER

Harry A. Douglas, Bronson, Mich.

Application December 22, 1932, Serial No. 648,355
Renewed April 1, 1936

2 Claims. (Cl. 173—269)

This invention relates to connectors more particularly for electrical conductors.

Among other objects, the invention aims to provide an improved line connector in which insulating coupling members maintain the conductors in engagement.

The invention is of particular utility when embodied in a test plug connector for laboratory and test equipment.

Other objects and advantages will be apparent from the following description taken together with the accompanying drawing showing an illustrative embodiment of the invention.

In the drawing—

Figure 1 is a longitudinal view of a connector assembly incorporating my invention;

Figure 2 is a longitudinal section of the connector shown in assembly in Figure 1, on a somewhat larger scale;

Figure 3 is a cross-section taken on the line 3—3 of Figure 2;

Figure 4 is a cross-section taken on the line 4—4 of Figure 1; and

Figure 5 is a fragmentary view showing a modification.

In the illustrative construction, my improved connector 1 includes a pair of electrical conductors here represented by the generally cylindrical metallic plug 2 and the metallic sleeve 3, the latter being associated with a current conducting wire 4 having the usual insulation 5 thereon. The plug 2 at one end is axially recessed as at 6 and the plug is flared thereabouts as at 7 to provide an external annular shoulder. The insulating coupling member 8 is also generally cylindrical and has a cylindrical bore 9 longitudinally therethrough which receives the plug 2. An internal formation such as the annular shoulder 10 in the bore of the member 8 abuts the flare 7 of the plug to limit relative movement of the plug and coupling member 8 in one direction. The plug 2 may be inserted in the member 8 from the right hand end of the member as shown in Figure 2 until the shoulders 7 and 10 abut, the plug being of sufficient length so that its end opposite the shoulder 7 then projects through the opposite end of the member 8 a suitable distance as shown, when the invention is used in the herein described specific exemplification.

The metallic sleeve 3 which forms a part of the other conductor here referred to is shown split longitudinally at one end to provide a plurality of, in this instance three, spring tongues 11. At their free ends these tongues desirably

carry radial enlargements 12. At its opposite end the sleeve 3 has a reduced extension 13. The wire 4 with its insulation 5 thereon is passed through the sleeve 3, the end of the wire being bared of its insulation and bent back over the reduced extension 13 as at 14. The extension 13 may be longitudinally grooved as by being depressed at 15 to receive the bent back end 4 of the wire.

Another insulating coupling member 16 has a bore 17 which receives the wire and sleeve 3, the wire being passed through the left hand end of the coupling and out the right hand end to be continued to a suitable source of electric current (not shown). The coupling member 16 has an internal formation adapted to abut the sleeve 3 to limit relative longitudinal movement of the sleeve and member 16, but in this instance this formation also acts as a cam surface to press the tongues 11 radially into engagement with the insulation 5 to clamp the sleeve upon the insulation, the inner surfaces of the tongues 11 advantageously having teeth 18 thereon, formed for example by screw threading the interior of the sleeve, to bite into the insulation 5. For this purpose, the bore 17 is here shown constructed as at 19 to form an annular tapering surface upon which the enlargements 12 of the tongues 11 ride as the sleeve and coupling 16 are moved relatively longitudinally in one direction.

To interengage the conductors the extension 13 of the sleeve 3 is adapted to be received in the recess 6 of the plug 2, the bore 9 of the coupling member 8 being enlarged as at 20, to at this time receive the sleeve 3 itself therein. The end of the coupling member 8 thus receiving the sleeve 3 is at the same time received in the bore 17 of the coupling member 16 annularly of the sleeve 3. The telescoping ends of the coupling members 8 and 16 are respectively exteriorly and interiorly threaded to provide the complementary screw threads 21. When the coupling members 8 and 16 are screwed together as shown, the plug 2 is held against relative movement with respect to the coupling member 8, while the sleeve 3 is forced axially of the plug 2 and coupling member 8 as far as the extension 13 will go into the recess 6 and normally until the wire 4 is clamped between the bottom wall 22 of the recess 16 and the extension 13. At the same time, since some relative movement between the sleeve 3 and coupling member 16 is permitted by the tapered surface 19, the tongues 11 are forced radially into engagement with the insulation 5. Thus the farther the members 8 and 16 are screwed together

the tighter will be the engagement between the plug 2 and sleeve 3 and between the sleeve 3 and the wire 4.

The insulating coupling members 8 and 16 are desirably formed of moulded phenolic condensation product and are provided on their outer peripheries, respectively, with knurlings 23 and 24, whereby they may be relatively rotated to be screwed together as described.

10 A tapered tip 25 may be formed on the exposed end of the plug 2 which may be readily inserted in a socket member 26 carried by an insulating panel 27 to make an electrical connection with another wire (not shown) which may be connected with another socket member 28 at the opposite side of the panel. The socket member 26 may have a cylindrical socket 29 therein extending axially thereof and a ball detent 30 may be pressed into this socket 29 by a resilient metal 15 split-ring 31 carried by the socket member 26, the tip 25 of the plug 2 having an annular depression 32 therein into which the ball 30 snaps to make a yielding but firm connection between the socket member 26 and the plug 2. The socket member 26 is more specifically described and claimed in my copending application, Serial No. 20 648,354 filed December 22, 1932.

So constructed and arranged, the connector 1 is especially adapted for laboratory or test work, 30 since the plug 2 is in improved mechanical and electrical engagement with the wire 4 and the connector may be quickly, but securely snapped successively into one after another of a number of sockets similar to the socket 26 carried by the 35 panel 27. The insulating coupling members 8 and 16 together make a convenient handle for the plug 2 as well as an insulator therefor. When it is desired to pull the plug out of the socket, the wire 4 may be pulled upon without danger of 40 disrupting its attachment to the connector 1, since the harder the wire is pulled upon, the tighter will the tongues 11 be clamped upon the insulation 5. Thus the connector is capable of withstanding 45 great abuse and the severe and constant service required of a test plug connector.

As shown in Figure 5, a plug 33 may be substituted for the plug 2 when a prod test plug is

desired, that is one which merely is touched to another conductor. In this modification the plug 33 may have a simple conical tip 34 terminating in a somewhat sharp point 35.

Having described my invention, I claim:

1. An electrical conductor including a cylindrical metal plug having an axial recess at one end and that end being provided with an annular exterior shoulder, a metallic sleeve having a reduced extension slidably mounted within said plug recess and being counter-bored to receive an insulated electrical conductor and to allow the bared conductor to pass therethrough to engage the plug within said recess, the exterior portion of the sleeve being split longitudinally to form means to clamp the insulation of the conductor and terminating in an annular exterior shoulder, in combination with two threaded interlocking members of insulating material, one of said members being axially bored to receive the cylindrical plug and being counter-bored to receive said plug shoulder and sleeve mounted therein and the other of said members being axially bored to receive the insulated conductor, said bore decreasing in diameter toward the outer end for engaging and coacting with the sleeve shoulder as the said members are threaded one upon the other for wedging the split sleeve upon the insulation of the conductor and clamping the conductor in engagement with the plug. 15

2. In combination: a body, including a pair of members each carrying means cooperable to effect connection of said members and each apertured to form a composite aperture extending longitudinally of said body; an electrical conductor member, having a part disposed within said composite aperture, and a part communicating with the exterior of said body; means disposed within said composite aperture, and having a part movable radially inwardly to grip a portion of an electrical conductor; said body members when connected acting on said means to urge said means toward said conductor member and hold the electrical conductor in position in electrical engagement with said conductor member; said body members being of insulating material. 35
